(57) **CLAIM**

The ornamental design for a control, as shown and described.

DESCRIPTION

In a preferred embodiment, the nature of this product is as a control, for example an electronic control for controlling the refrigeration components of a cooling unit, such as a compact refrigerator, freezer, beverage cooler, ice maker, combinations thereof and the like.

FIG. 1 is a right, top, front perspective view of a control embodying our new design;

FIG. 2 is an enlarged perspective view thereof;

FIG. 3 is an enlarged front elevational view;

FIG. 4 is an enlarged top plan view thereof; and,

FIG. 5 is an enlarged right side elevational view thereof, the left side elevational view is a mirror image.

The broken lines shown in the drawing disclosure are for illustrative purposes only and form no part of the claimed design.
